ALFRED HOFFBAUER, OF BROOKLYN, NEW YORK, ASSIGNOR TO THE AMERICAN SUGAR REFINING COMPANY, OF NEW YORK, N. Y., A CORPORATION OF NEW JERSEY.

VARIABLE-SPEED DRIVING MECHANISM.

1,410,305.

Specification of Letters Patent. Patented Mar. 21, 1922.

Application filed August 14, 1920. Serial No. 403,594.

To all whom it may concern:

Be it known that I, ALFRED HOFFBAUER, a citizen of the United States, residing at Brooklyn, in the county of Kings, State of New York, have invented certain new and useful Improvements in Variable-Speed Driving Mechanism; and I do hereby declare the following to be a full, clear, and exact description of the invention, such as will enable others skilled in the art to which it appertains to make and use the same.

This invention relates to a device adapted to produce variable movement of mechanism in which it is desirable that a part should travel at different velocities during selected portions of its cycle. The invention is particularly useful and desirable in connection with an operation of means for washing the leaves of a filter, where the washing means is directed against varying areas of the leaves during the operation. It is to be understood, however, that the device hereinafter described, is not limited to the particular purpose set forth, but is of general application, and may be employed in any connection where the result accomplished thereby is desired.

In order that the purpose may be clear, reference is made to the application of the device to a filter, which may consist of a roughly cylindrical chamber, having a plurality of leaves supported therein, and adapted for use in separating solids from liquids, in a manner well understood in the art. In such a filter, it is customary to provide an oscillating tube or manifold having nozzles thereon, which direct streams of liquid against the sides of the respective filter leaves as the tube oscillates. Obviously if the leaves are circular in form, the area against which the jets or streams of liquid are directed, varies during the oscillation of the tube, and consequently, if the tube is oscillated at a uniform angular velocity, the washing of the leaves at the portions remote from the center will be much more thorough than at the central portion, where the area to be treated is considerably larger. To meet this difficulty, it has been customary heretofore, to provide the tube with a handle, and to employ a workman who is taught to manipulate the tube in such a manner that the rate of travel of the jets across the central portion of the leaves is considerably slower than the rate at the ex-

tremities of the oscillation. The manipulation of the tube in this manner is somewhat difficult, and because of the effort required, the workman is inclined to neglect his instructions, so that the method employed is unsatisfactory both from the standpoint of results obtained, and of the cost of producing these results.

To meet this condition and to mechanically operate the washing tubes of one or more filters, it is desirable to provide means for imparting to the tubes the desired oscillating motion, that is, a comparatively rapid movement near the opposite ends of the oscillation with much slower movement during the middle period of travel. This result has been accomplished by the provision of substantially elliptical sprockets connected by suitable chains to driving and driven sprockets of the usual form, which are in turn connected through mechanical connecting means to a source of power, and to the tube or tubes to be oscillated. Because of their peculiar shape, the elliptical sprockets impart to the driven sprockets, a movement, which conforms exactly to that desired, and may be readily transmitted to the washing tube of a filter, or to any other mechanism which is to be operated in a similar manner.

The objects and advantages of the invention will be more clearly understood by reference to the following specification and accompanying drawing, in which—

Fig. 1 is an elevation of the device illustrating the application thereof to a filter of the type referred to, and,

Fig. 2 is a plan view of the structure illustrated in Fig. 1.

Referring to the drawing, 5 indicates the shell or housing of a filter, which may contain a plurality of leaves 6, each connected to a suction means, (not shown) whereby liquid is withdrawn from the shell or casing, while the solids are deposited upon the leaves. The form and structure of the filter forms no part of the present invention and may be widely varied, and the illustration thereof herein, is merely for the purpose of clearly defining the problem which has been met and overcome by the present invention. As above noted, filters of the type referred to are provided with a tube 7 extending longitudinally thereof, and provided with a plurality of nozzles 8, which direct streams of a liquid, against the face of the filter leaves. 110

The tube is connected through a stuffing box to a source of liquid for example water, under the necessary pressure, so that the tube may oscillate under the actuating mechanism to deliver the jets to the filter while the tube is oscillating.

The device is supported on a frame 9 which may be disposed in any suitable relation to the filter and provides bearing 10 supports for the shafts of the device. A motor 10 may be supported on the frame; although power from any source may be utilized. Preferably the motor is connected by a belt 11 to a pulley on a counter-shaft 9. A motor 10 may be supported on the frame; although power from any source may be utilized. Preferably the motor is connected by a belt 11 to a pulley on a counter-shaft 9. A pinion 16 on the shaft 14 meshes with a gear 17 on a shaft 18, which is supported in bearings 19 spaced from the bearings 15 on the frame. The shaft 18 carries a sprocket 20 of the usual form, and a chain 21 connects this sprocket to a sprocket 22 which is substantially elliptical in form, and is mounted on a shaft 23. The shaft 23 is supported in bearings 24 spaced from the bearings 19 on the frame, and carries a sprocket 25 also substantially elliptical in form, and arranged with its longer axis substantially perpendicular to the longer axis of the sprocket 22. A chain 26 connects the sprocket 25 to a sprocket 27 of the usual form supported on a shaft 28 which is mounted in bearings 29 spaced from the bearings 24 on the frame. The several pulleys, gears and sprockets are so proportioned as to impart to the shaft 28 the desired speed of rotation, and the provision of the elliptical sprockets 22 and 25 insures that the sprocket 27 will rotate at a non-uniform velocity, the angular velocity of the latter sprocket being successively rapid and slow, in order that the desired movement may be imparted to the washing tube of the filter.

To apply this movement to the washing tube, the shaft 28 is provided with a crank 30, which is connected by a link 31 to a lever 32 pivoted at 33 on a depending lug 34, for example, of the frame. If a plurality of washing tubes in a number of filters are to be actuated in the manner described, the lever 32 may be connected to a reciprocating rod 35, preferably by a pin 36 which travels in a slot 37 in the lever. The rod 35 may be supported in suitable hangers 38, having rollers 39 to reduce friction. As it is desirable that the individual filters may be disconnected from the rod from time to time, the latter is provided with links 40 pivoted at 41, each having a pin 42, which is adapted to enter a recess near the end of an operating lever 43, connected to the tube 7 of a filter. A locking

device 44 is provided to prevent escape of the pin 42 from the recess in the lever 44.

When the lever 43 is thus connected to the rod 35 the reciprocating motion of the rod is applied to the oscillation of the washing tube in the filter. The reciprocating movement of the rod, owing to the shape of the elliptical gears, is relatively rapid at the beginning and near the end of the stroke, but during the intermediate portion, the rate of travel is sufficiently slow to insure the delivery of the required amount of water to the filter leaves for the purpose of completely washing the material thereon. Thus the difficult manual actuation of the washing tubes is avoided, and the tubes are oscillated with precise and absolute uniformity. The desired angular velocity of the tubes at any point during the oscillation may be readily determined, and the elliptical gears are so proportioned as to produce this result. A relatively small amount of power is required to oscillate the tubes of a considerable number of filters, so that there is the advantage of reduced cost in maintaining the desired operation, in addition to the uniformity of the operation, the securing of which is the primary object of the invention. The invention may obviously be applied to the operation of a single washing tube or in fact to the actuation of any mechanism in the manner described.

As will be readily understood from the foregoing, the device herein described is simple in construction, so that it is adapted for successful operation without attention under the conditions prevailing in filter houses and like situations. The device may similarly be adapted for various purposes, and should therefore be considered as a mechanical movement capable of converting rotational movement at uniform angular velocity into rotational or rectilinear movement at variable velocity.

Various changes may be made in the form, arrangement and construction of the parts, without departing from the invention or sacrificing any of the advantages thereof as hereinbefore set forth.

I claim:

1. A mechanical movement adapted to convert rotational movement at uniform angular velocity into similar movement at non-uniform angular velocity, including a shaft, a pair of elliptical sprockets on the shaft with their longer axes arranged in substantially perpendicular relation; means for driving one of the sprockets, and means for transmitting movement of the other sprocket under the actuation of the driving means.

2. A mechanical movement adapted to convert rotational movement at uniform angular velocity into similar movement at non-uniform angular velocity, including a plu-

- rality of shafts arranged in spaced relation, circular sprockets on two of the shafts, two substantially elliptical sprockets on another shaft, chains connecting the elliptical to the 5 circular sprockets, means for imparting movement to one of the circular sprockets, and means for transmitting the movement of the remaining circular sprocket.
3. In a device for actuating the washing 10 tube of a filter and imparting oscillating movement to the tube at varying angular velocity, including a substantially elliptical sprocket, driving means connected thereto, and means for transmitting movement from 15 the sprocket to the tube.
4. In a device for actuating the washing 20 tube of a filter, and imparting oscillating movement to the tube at varying angular velocity, including a shaft, a pair of substantially elliptical sprockets thereon, driving 25 means connected to one of the sprockets, and means for transmitting the movement of the other sprocket to the tube.
5. In a device for actuating the washing 30 tubes of a plurality of filters, and imparting oscillating movement to the tubes at varying angular velocity, including a shaft, a pair 35 of substantially elliptical sprockets thereon, means for actuating one of the sprockets, and means for transmitting movement of the other sprocket to the respective tubes.
6. In a device for actuating the washing 40 tubes of a plurality of filters, and imparting oscillating movement to the tubes at varying angular velocity, including a shaft, a pair 45 of substantially elliptical sprockets thereon, means for actuating one of the sprockets, means for transmitting movement of the other sprocket to the respective tubes, and means whereby movement of any tube may 50 be discontinued.
7. In a device for actuating the washing tubes of a plurality of filters, and imparting oscillating movement to the tubes of varying angular velocity, including a shaft, a pair 55 of substantially elliptical sprockets on the shaft with their longer axes arranged in substantially perpendicular relation, means for actuating one of the sprockets, and means for transmitting movement of the other sprocket to the respective tubes.

In testimony whereof I affix my signature.

ALFRED HOFFBAUER.
